UNITED STATES PATENT OFFICE

LEON F. DOUGLASS, OF MENLO PARK, CALIFORNIA

DESIGN FOR A LIGHTER

Application filed November 2, 1929. Serial No. 33,265. Term of patent 3½ years.

• To all whom it may concern:

Be it known that I, LEON F. DOUGLASS, a citizen of the United States of America, residing at Menlo Park, in the county of San Mateo and State of California, have invented a new, original, and ornamental Design for a Lighter, of which the following is a specification, reference being had to the accompanying drawing, forming a part thereof, in which

Fig. 1 is a side view of a lighter illustrating my new design; and

Fig. 2 is a top view of the same.

I claim:

The ornamental design for a lighter as shown.

LEON F. DOUGLASS.
